ALBERT A. WOOD, OF ATLANTA, GEORGIA.

BOTTLE-SEALING CAP.

SPECIFICATION forming part of Letters Patent No. 777,168, dated December 13, 1904.

Application filed March 22, 1904. Serial No. 199,385. (No model.)

To all whom it may concern:

Be it known that I, ALBERT A. WOOD, of the city of Atlanta, in the county of Fulton and State of Georgia, have invented certain Improvements in Bottle-Sealing Caps, of which the following is a specification.

This invention relates to certain improvements in bottle-sealing caps which embody as essential features thereof a crown having a pendent flange the lower edge of which is adapted to be turned in and under a shoulder generally produced in bottles by the projection of the head beyond the neck to hold the crown in contact with the lip of the bottle and a joint-forming ring or gasket which is inclosed by the pendent flange and sustained in contact with the crown.

The said invention consists in a peculiar formation of the cap whereby it is adapted for application to bottles varying in diameter of exterior lip and to those wherein the extreme end of the bottle is not at a right angle with the vertical center line or axis of the bottle or where by reason of the bottle not standing in a vertical position on its seat during the sealing operation the end of the lip does not present a horizontal surface to the part of the sealing-machine which forces the crown of the cap in contact with the bottle, as will hereinafter fully appear.

In the further description of the said invention which follows reference is made to the accompanying drawings, forming a part hereof, and in which—

Figure 1 is an exterior side view of a bottle-head with the improved sealing-cap thereon, the said cap being shown in section and in the position which it occupies before it is secured in place. Fig. 2 is a top view of Fig. 1. Fig. 3 is a vertical section of the bottle-head and the cap, illustrating the shape of the cap after the sealing operation should the bottle-head be slightly smaller in diameter than the average size. Fig. 4 is a view similar to Fig. 3, except that the bottle-head shown therein is slightly greater in diameter than the average head. Fig. 5 is a view similar to Fig. 4, illustrating the shape of the cap when affixed to a bottle-head the end of which is

not at a right angle with the vertical center line of the bottle. Fig. 6 is a top view of Fig. 5. Fig. 7 is a top view of the joint-forming ring or gasket. Fig. 8 is an enlarged section of a part of Fig. 4. Fig. 9 is an enlarged section of a part of the sealing-cap and its joint-forming ring or gasket, showing the latter before it is fully in place in the cap. Fig. 10 is an enlarged sectional view of a part of several sealing-caps, showing the same as nested and illustrating a feature hereinafter described.

Referring now to Figs. 1 and 2 of the drawings, 1 is a bottle-head having the usual shoulder 2. The bottle-cap, which is preferably formed of sheet-aluminium, consists of the crown 3, the pendent annular flange 5, and the compressible joint-forming ring or gasket 7, which is pressed tightly into contact with the crown. In the formation of the cap there is produced in the crown thereof the flat annular surface 9, against which the gasket 7 rests, and within the circumference of the said surface the annular downwardly-extending V-shaped projection 10, which as the cap is placed loosely on the bottle-head will rest on its extreme end or in case of a gasket being in place will come nearly in contact therewith, as shown in Fig. 1. To effect a well-defined projection of the character described, the central portion of the crown is by preference made concave as viewed from underneath; but any other shape that will effect this result could be employed without deviating materially from the present invention. The object of the annular projection 10 is to give to the cap an element which will readily and easily adapt itself to the surface of the bottle with which it is forced in contact in the sealing operation, and thereby produce a joint which is nearly a tight one without respect to the compressible gasket, which is ultimately depended on to fully and effectually close the bottle.

By reference to Fig. 3, which represents the bottle-head, gasket, and cap after the sealing operation, it will be seen that the hollow projection 10 is entirely effaced; but this is effected only when the extreme end of the bottle is free from any inequalities in its surface or when

at the time of the sealing operation the same is in a strictly horizontal position; otherwise the said projection will appear in part. This latter condition is well shown in Fig. 5, where 5 the end of the bottle is shown as inclined with respect to the central vertical line, a trace of the projection being visible to the right of the said figure and also in Fig. 6, which is a top view of Fig. 5.

10 From the foregoing description it will be understood that in the annular projection 10 of limited area the caps are furnished with an element which adapts itself to bottles in all circumstances and under all conditions and one 15 that is free from recoil and will retain any modification in shape given it in the sealing operation.

By reference to Figs. 1, 7, and 9 it will be seen that the compressible joint-forming ring 20 or gasket 7 is rectangular in cross-section, and by particular reference to the last-named illustration that its outer diameter is greater than that of the body of the flange of the cap or the part thereof adjoining the crown. The 25 packing-ring has, therefore, to be slightly compressed in order to place it in position, and to facilitate the introduction of the gasket into the cap the lower portion of the flange, or that part thereof which is ultimately turned in and 30 under the shoulder of the bottle-head to secure the cap to the bottle, as shown in Figs. 3, 4, 5, and 8, is flared, as represented in Figs. 1, 9, and 10.

In Fig. 9 the gasket is illustrated as within 35 the flared portion of the flange and in contact with the annular corner formed by the junction of the flared and cylindrical portions of the flange.

In Figs. 1 and 3 the sealing-cap is shown as 40 applied to a bottle-head of the standard size, and in this case in the sealing operation, in which the cap is flattened, sufficient room is left between the cylindrical portion of the flange and the exterior surface of the bottle-lip to accommodate the compressed gasket 45 without changing the shape of the flange. The same condition is maintained should the bottle-head be a little smaller than the standard size; but if the cap is applied to a bottle 50 exceeding in diameter the standard size, as in Figs. 4, 5, and 8, the reduction in space allowed for the compressed gasket will cause a

distortion of the flange or its outward rounding or bulging, as shown in the said figures.

From the foregoing description it will be 55 understood that the improved sealing-cap is adapted to all the various conditions found in bottle-heads, all deviations from a standard size and shape being provided for.

Fig. 10 is for the purpose of illustrating 60 how the sealing-caps will nest without adhering one to another. This non-adhesion of the caps is an important matter, as in the machine whereby the capping operation is performed and which will form the subject of a future 65 application the caps are placed as shown in that figure in order that they may be fed separately to bottle-heads.

I claim as my invention—

1. In combination with a bottle-head having 70 an exterior shoulder, a cap for the same which embodies a crown and a pendent annular flange, and a contained joint-forming gasket, the inner surface of the said crown being provided with a pendent annular projection 75 adapted to come in contact with the exterior lip of the bottle, and in the sealing operation conform to the surface of the said lip, independently of the portion of the crown directly over the throat of the bottle, substantially as, 80 and for the purpose specified.

2. A sealing-cap for a bottle which consists 85 of a crown having a downwardly-extending annular projection adapted to come in contact with the extreme end only of the bottle to which it is applied, a pendent annular flange, and a contained joint-forming gasket or packing-ring, substantially as, and for the purpose specified.

3. A sealing-cap for a bottle which comprises 90 a crown having a downwardly-extending annular projection adapted to come in contact with the extreme end only of the bottle, a practically cylindrical pendent flange having a flaring extremity, and a compressible joint-forming ring or gasket which is 95 slightly larger in diameter than the said cylindrical portion of the flange, and smaller than its flaring extremity, substantially as, and for the purpose specified.

ALBERT A. WOOD.
